GLOW-DISCHARGE VESSEL FILLED WITH
GAS OR VAPOR

Johannes Nienhold, Berlin-Charlottenburg, Germany, assignor to Siemens & Halske, Aktiengesellschaft, Siemensstadt, near Berlin, Germany, a corporation of Germany

Application December 16, 1932, Serial No. 647,554
In Germany December 18, 1931

12 Claims. (Cl. 250—27.5)

This invention refers to an improvement of gas- or vapor-filled glow-discharge vessels, having a hollow cathode. Where in the following description and in the appended claims reference is made to a glow-discharge hollow cathode, this is understood to be a cathode subdivided so as to form spaces or compartments, the different component parts of such cathode being arranged in such a manner and at such a distance apart that the electrons liberated from one portion of the cathode by the impingement of positive ions are shot into the cathodic fall space of the opposite part of said cathode and are stopped in this fall space, thus giving rise to a concentration of electrons in the hollow spaces of the cathode and, consequently, to a reduction of the cathode fall.

A glow-discharge hollow cathode is more particularly understood to be also such a one of the type characterized above, in which the distances separating the opposite hollow cathode surfaces are equal or inferior to the fall space thickness at a simple cathode.

In the accompanying drawing, Fig. 1 is a diagram illustrating the discharge conditions; Figs. 2, 3, 5, 6, 7 and 8 are vertical sections illustrating various embodiments of my invention; and Fig. 4 is a perspective view of a perforated hollow cylinder such as I employ in some of the embodiments shown.

In glow-discharge vessels having such glow-discharge hollow cathodes, the operating conditions employed prior to my invention are such as are represented, for instance for small gas pressures in Fig. 1.

The discharge current *i* has been plotted as abscissa and the filament voltage *e* as ordinate. On applying a voltage to the vessel the voltage must, for instance, be raised to 300 volts (section *a*—*b*). At this voltage, a low discharge, known to-day usually as "preliminary discharge", is started, while the voltage simultaneously decreases to 200 volts (section *b*—*c*). For further increase of the filament voltage the discharge current increase is comparatively slight, so as to give a steep rise of the characteristic line (section *c*—*d*). At 900 volts, point *d*, the preliminary discharge suddenly becomes the glow-discharge strictly speaking, the voltage dropping from 900 volts to about 180 volts (section *d*—*e*). The voltage of 180 volts depends, of course, on the series resistance. The discharge current intensity decreases considerably with increasing filament voltage (section *e*—*f*). At point *f*, the glow-discharge is converted into the arc dis-

charge (section *f*—*g*), which involves a voltage drop of from say 400 volts to 15–20 volts. The range *g*—*h* is the arc discharge range. As may be seen from the characteristic line, a very high voltage should be applied at least once, in order to obtain appreciable discharge currents, i. e. at least one glow-discharge. In the case of the example, it was necessary to raise the voltage once up to 900 volts for a mean operating voltage and for a glow discharge of 200–400 volts. The smaller the gas pressure, the higher the maximum voltage to be applied before the starting of the glow-discharge. The same holds for small cathode distances. The dotted curve *c*—*k* indicates, for instance, such a characteristic for small gas pressures and short cathode distance. With an extremely small gas pressure, it may occur that, even for voltages of several thousand volts, the preliminary discharge does not become a glow discharge since in the working range the discharge is obstructed.

According to the invention, these drawbacks are avoided by providing in glow-discharge vessels filled with gas or vapor and having a glow-discharge hollow cathode, as defined above, suitable means for obtaining a supplementary thermal production of electrons in the hollow spaces. For this purpose devices well-known in themselves are available. The method of making hollow cathodes highly emissive by the use of adequate material is well-known in the art. The inner surfaces of hollow cathodes are, for instance, coated with alkali earth metals or oxides of electro-positive substances or finely sub-divided compounds of the two. An appropriate design of the cathode, with respect to the working current, permits one also to obtain a certain self-heating effect, which is, however, only obtained after at least the range of high glow-discharge currents has been reached. Thus these means do not result in a considerable reduction of the voltage peak (point *d* in Fig. 1). Only an additional source of thermions, as employed in this invention, enables a direct passage to be obtained from point *c* to point *e* so that the peak is avoided (hatched range).

The thermionic source can be designed in two ways. Either use is made of an incandescent cathode, of a type known in the art, for instance, an oxide-coated, distillation or thoriated cathode, or provision is made for additional heating enabling the hollow cathode or at least parts of it to emit ions thermically.

The first case in which use is made of a direct-acting incandescent cathode has been represented

in Fig. 2. The holding wire 2 sealed into the squash 1 carries the glow-discharge hollow cathode 3 which has been given the shape of a box. It consists of a casing 4 surrounded by a heat-protecting envelope 5. Within the cathode there are located the intermediate sheets or partitions 6, 7 and 8, which are bored through in the middle, so as to enable the helical filament 10 carried by the electrode holding wire 2 or its extension 9 to project into the whole of the compartments formed by the said partitions, which compartments in this particular example are designated by 11, 12, 13 and 14. The helical filament is at one end supported by the holding wire 15, which is insulated by means of an insulating tube 16 and led through the casing 4 and the heat-protecting envelope 5. Of course the filament can be given any other form. The lead to the filament, which may also be a stretched filament, may be insulated at both ends, a fact which is of importance for A. C. operation. It is also possible to establish an electric connection between the electric center of the filament and the hollow cathode system.

Another example of the use of a directly heated cathode is given by Figs. 3 and 4. The two electrode holding wires 18 are sealed into the squash 17. They carry the hollow cathode which is, in this case, built up of concentrical cylinders 21 and 22 arranged in the casing 19 surrounded by the heat-protecting envelope 20. These cylinders are shaped as indicated in Fig. 4, i. e. they have slots enabling the various compartments of the cathode system to communicate with one another. Within the hollow cylinder 21, there is located a double-wound helical filament 23 carried by the two electrode holding wires 24 and 25. The slots of the different hollow cylinders are designed so as to enable the electrons emitted within the hollow cylinder 21 to penetrate into the other compartments. The barium vapor cloud formed by the thermite pill 26 (compound of barium oxide and aluminium) can also during the manufacturing process penetrate through the slots into all the compartments.

When starting a hot cathode such as indicated in Figs. 3 and 4, it is found that the glow-discharge within cylinder 21 is first started and that, due to the superposed discharge current, the hot cathode is then brought to a brighter glow (additional self-heating). The discharge shifts to the remaining hollow cylinders, the hot cathode again assuming its normal temperature.

When the glow-discharge is started, it is, with a suitable design of the cathode, possible to switch the hot cathode off or to keep it burning at a dark-red glow.

Figs. 5-8 show the hollow cathodes, as heated indirectly according to the invention.

In Fig. 5, the electrode holding wire 28 sealed into the squash 27 carries the glow-discharge hollow cathode 29 which, as shown in the constructional example of Figs. 2-4, consists of a casing or cylinder 30 which may be surrounded by a heat-protecting envelope 31. Within 30, there is, for instance, a hollow cylinder 32, and, in its center a convex bulge 33 containing within its inner concave part a heater 34 heated, for instance, through the lead 36 surrounded by an insulating tube 35. After switching on the heater, 34, the part 33 is heated up, so that its outer surface is caused to emit electrons. In the case of A. C. heating, it may be electrically recommendable to separate the heating wire 34 completely from the hollow cathode system. In the case of the above-described glow-discharge hollow cathode also, the

inner cylinder 32 or the partitions should be equipped with openings, so as to enable the electrons proceeding from the outer surface of the cylinder 32, to penetrate into all the compartments under consideration.

Fig. 6 shows another constructional example of the glow-discharge hollow cathode. The squash 37 carries the holding wire 38 for the hollow cathode 39. This hollow cathode consists of a tube 40 closed at the top and containing a heater 41 heated in a manner well-known in the art. The tube 40 carries spaced circular ribs 42 so that compartments 43, 44, 45 etc. are formed. It may be suitable in this case to coat the tube parts 46, 47 between the ribs 42 with an electron-emitting material, e. g. oxide or the like, in order to obtain, within the limits possible, a high electronic output. If the heating is sufficient, the ribs are also heated and it may then be desirable to coat these ribs as well with an electron-active material or to construct them throughout of such material (for example thoriated tungsten or the like).

Figs. 7 and 8 show discharge vessels according to my invention, in which the heating is indirect, the heater, however, being located outside the discharge vessel, that is not within the vacuum. In this way the heaters can be readily interchanged and the discharge vessels can more particularly be adapted for any given working conditions by the insertion of an adequate heater body.

Fig. 7 shows a vessel in which the heater is located within a small bay of the discharge vessel. The metal pot 50 is sealed at 49 into the discharge vessel 48 consisting for instance of glass and carrying the glow-discharge hollow cathode 51. This cathode is constructed in much the same manner as in the previous example. The heater 52 which is placed within the metal pot 50 heats the outer walls 53, 54 sufficiently to enable them to emit electrons. In order to economize as much as possible on heat, it may be advisable to give the metal pot 50 a tapered cross-section, say at the point 55, so as to minimize the conduction of heat.

Another constructional example of heating from the outside is shown in Fig. 8. The discharge vessel 56 is here sealed into a metal pot 57, containing the ribs 58, 59 etc., which form the different chambers or compartments of the glow-discharge hollow cathode. A heater 60 shaped as a ring is placed around the metal pot from the outside, and raises the temperature of the cathode to a degree suitable for emission purposes. A tapered cross-section may be provided for at 61 in order to block the transmission of heat. On account of the great strain produced by the heating, the metal pots 50 of Fig. 7 and 57 of Fig. 8 should be made of metal not readily oxidized, for instance of chromic iron, nickel-iron or the like, or they should be coated with nickel-, chromium- or platinum-layers on the side exposed to the atmosphere.

As to the material for the cathode, I may use nickel, iron, molybdenum, tungsten, or the like, either in the compact condition or in the shape of a netting. As has been stated above, the emissive material should be either thorium in any of its different forms or alkali earth metals, as well as the oxides thereof. More particularly in the constructional examples shown in Figs. 7 and 8, materials should be used which even at extremely low temperatures will yield a high emission of electrons. Barium finely sub-divided with oxide, which even at temperatures below red-

glow will yield an appreciable emission, is of special suitability. The use of nettings (nickel) is here preferable, as it suits the emission-material particularly well. From the manufacturing standpoint nettings are also recommendable, since, for instance, barium-oxide can easily be rubbed into the meshes, and pure barium is present in the nettings after disintegration in vacuo.

As to the construction of the hollow cathode, the following is important: the distances separating the opposing hollow cathode surfaces should be in a definite ratio to the filling gas and to the gas pressure, i. e., the distances should be inferior or equal to the width or thickness which the fall space has in the case of a cold simple cathode under corresponding conditions as to kind and pressure of the gas or vapor employed. By a simple cathode, I mean one made of sheet metal, a so-called plate cathode, opposite to which an anode is located at a relatively considerable distance. This distance varies with the kind of gas or vapor employed and with the pressure under which such gas or vapor is contained in the vessel. These distances, insofar as they cannot be determined by experiment, can be calculated roughly, by making them equal to 10 to 20 times the length of the mean free gas-kinetic electron path.

The electron path length within a gas or vapor having a pressure of p mm. is:

$$\lambda = \frac{4300}{p} \lambda_0,$$

where λ_0 is the mean free path of a neutral gaseous molecule which may be found in chemical tables. For mercury vapor, helium, argon and neon, the values for the electron path length in millimeters at a pressure p of 1 mm. and a temperature of 0° C., are as follows:

Hg	Ar	Ne	He
0.093	0.29	0.54	0.77

By multiplying these values by 10-20 we approximately obtain the fall space thickness at a gas pressure of 1 mm.

A distinguishing feature of my invention is the production of a peculiar effect known as the "hollow cathode effect". Investigations have shown that this effect is obtained when using a subdivided cathode having compartments the adjacent walls of which are spaced from each other a distance smaller than twice the thickness of the fall space. An explanation of this peculiar effect is found in various publications, see for instance Engel & Steenbeck's book "Elektrische Gasentladungen" Berlin 1934, Section 49 (pages 114 to 116).

What I claim as my invention is:

1. In a glow-discharge vessel filled with gas or vapor and having a glow-discharge hollow cathode, provided with compartments, the distance between the adjacent walls of such compartments being smaller than twice the thickness of the fall space, means for the additional thermic production of electrons within the compartments of the cathode.

2. In a glow-discharge vessel filled with gas or vapor and having a glow-discharge hollow cathode, provided with compartments, the distance between the adjacent walls of such compartments being smaller than twice the thickness

of the fall space, a hot cathode located within said glow-discharge hollow cathode.

3. In a glow-discharge vessel filled with gas or vapor, a glow-discharge hollow cathode provided with compartments, the distance between the adjacent walls of such compartments being smaller than twice the thickness of the fall space, said cathode containing an electric heater.

4. In a glow-discharge vessel filled with gas or vapor and having a glow-discharge hollow cathode, provided with compartments, the distance between the adjacent walls of such compartments being smaller than twice the thickness of the fall space, a heater located outside the discharge vessel.

5. In a glow-discharge vessel filled with gas or vapor and having a glow-discharge hollow cathode, provided with compartments, the distance between the adjacent walls of such compartments being smaller than twice the thickness of the fall space, a heater located outside the discharge vessel and surrounding said glow-discharge hollow cathode.

6. In a glow-discharge vessel filled with gas or vapor and having a glow-discharge hollow cathode, provided with compartments, the distance between the adjacent walls of such compartments being smaller than twice the thickness of the fall space, a heater located outside the discharge vessel within a bay of the walls.

7. In a glow-discharge vessel filled with gas or vapor and having a glow-discharge hollow cathode, provided with compartments, the distance between the adjacent walls of such compartments being smaller than twice the thickness of the fall space, a heater located outside the discharge vessel and within a bay having the shape of a sealed-in pot.

8. In a glow-discharge vessel filled with gas or vapor and having a glow-discharge hollow cathode a heater, provided with compartments, the distance between the adjacent walls of such compartments being smaller than twice the thickness of the fall space, located outside the discharge vessel in a bay having a tapered cross-section.

9. In a glow-discharge vessel filled with gas or vapor and having a glow-discharge hollow cathode provided with compartments, the distance between the adjacent walls of such compartments being smaller than twice the thickness of the fall space, and means for the additional thermic production of electrons in the compartments of said cathode, openings connecting said hollow spaces with one another and enabling the thermically produced electrons to penetrate into several compartments.

10. Glow-discharge vessel filled with gas or vapor and having a glow-discharge hollow cathode provided with compartments, the distance between the adjacent walls of such compartments being smaller than twice the thickness of the fall space, and means for insulating said hollow cathode from heat.

11. A device of the character described, comprising a glow-discharge vessel filled with gas or vapor and having a glow-discharge hollow cathode provided with compartments and in which the opposing surfaces of the different component parts are at distances from each other inferior or equal to the thickness which the fall space has in the case of a simple cathode under corresponding conditions as to kind and pressure of the gas or vapor employed, and means for the additional

thermic production of electrons within said cathode.

12. A device of the character described, comprising a glow-discharge vessel filled with gas or vapor and having a glow-discharge hollow cathode having opposing surfaces the distance between which is inferior or equal to the thickness

which the fall space has in the case of a simple cathode under corresponding conditions as to kind and pressure of the gas or vapor employed, and means for the additional thermic production of electrons within said cathode.

JOHANNES NIENHOLD.
